UNITED STATES PATENT OFFICE.

JOHN W. COSGROVE, OF MEDFORD, MASSACHUSETTS, ASSIGNOR TO UNITED SHOE MACHINERY CORPORATION, OF PATERSON, NEW JERSEY, A CORPORATION OF NEW JERSEY.

COATING APPARATUS.

Application filed September 18, 1919. Serial No. 324,529.

To all whom it may concern:

Be it known that I, JOHN W. COSGROVE, a citizen of the United States, residing at Medford, in the county of Middlesex and 5 State of Massachusetts, have invented certain Improvements in Coating Apparatus, of which the following description, in connection with the accompanying drawings, is a specification, like reference characters on 10 the drawings indicating like parts in the several figures.

This invention relates to the application of coating substances. In the coating of certain objects, as the layers of a built-up 15 sole of a shoe, such an adhesive as cement is applied to adjacent surfaces lying at an angle to one another, these being, for example, upon the inner face of an outer sole layer and the edge of a beveled shank 20 piece secured thereto, for the purpose of joining them to opposed surfaces, which may be one face of the next layer of the sole and its beveled edge. It is difficult to cement properly work of this character, 25 and an object of the present invention is to provide for quickly and uniformly coating such surfaces.

In the attainment of this object, there is furnished, as a feature of the invention, 30 an apparatus for applying a coating to such work as the inclined surfaces described above, said apparatus including an applying roll and a pressure roll having surfaces extending opposite each other from points 35 substantially at the extremities of the respective rolls for a distance as great as the width of one of the surfaces to be coated, and with the applying roll projecting beyond the pressure roll to a distance as great 40 as the width of the other surface to be coated.

By this arrangement an applying surface is given upon which the surfaces to be treated are straightened and coated, and the associated roll, while capable of exercising the alining pressure, leaves a space 45 into which the work may be bent in the operation.

A further feature of the invention concerns the establishment of a desired angular 50 relation between the axes of the work-engaging rolls, thus permitting the correction of errors in parallelism between their co-operating peripheral portions, and insuring such a pressure upon the work as to bring 55 the surfaces to be coated in correct aline-

ment and contact with the applying roll. To this end, one of the rolls is movably mounted, and there is means for fixing it in its adjusted position. Preferably, the mounting is pivoted to enable the angular 60 adjustment to be effected. Furthermore, to adapt the apparatus to operate upon work of different thickness, one of the rolls may be yieldably mounted. I have herein shown the adjustable roll and its mounting arranged to yield together. 65

In the following description these and other features will be developed in connection with the accompanying drawing, in 70 which—

Fig. 1 is a top plan view of one embodiment of the invention;

Fig. 2 is a front elevation thereof;

Fig. 3 is an end elevation, looking from 71 the left in Fig. 2;

Fig. 4 shows in detail, in side elevation, the scraping devices for the applying roll; and

Fig. 5 is a view in side elevation of a 80 shoe sole which may be cemented by the apparatus of the present invention.

The main frame of my improved apparatus consists of a tank or receptacle 10 for the cement or other coating substance, this tank having projecting from one side an 85 arm 12. The contents of the tank may be heated by electric units inserted in recesses 14 in the bottom. This bottom portion of the tank is shown as corrugated at 15, this increasing the heated area and more effectively maintaining the cement fluid. The bottom is preferably inclined toward the center of the tank, and from this point a 90 passage leads to an opening at one side of the bottom, this being closed by a screw plug 16, which when removed will permit the contents of the tank to be drained off.

In bearings in the end walls of the tank is journaled a shaft 18, having fixed upon it and extending practically the full width of the tank an applying roll 20. To bring up the cement from the body in the tank and effectively distribute it over the work, the periphery of the applying roll is provided with a circumferential series of 105 shallow and slightly spiral grooves 22. Secured to the shaft 18 outside the tank is a gear 24 meshing with an idler gear 26 rotatable about a short spindle 28 projecting from one of two spaced upwardly extend- 110

ing branches 36, 36 of the arm 12. The idler 26 in turn meshes with an elongated pinion 30 fastened upon the side of a driven pulley 32, the pinion and pulley being rotatable about a spindle 34 fixed in the upper extremities of the arm branches 36. Adjacent to the pulley 32 is a loose pulley 38, there being a shifting device 40 provided to carry the driving belt (not shown) from 10 one pulley to the other. By this gearing the roll 20 is rotated in the direction indicated by the arrow in Fig. 3 of the drawings.

At the rear of the applying roll in the 15 upper edges of the end walls of the tank are ways 42, 42 to receive a scraper 44 extending at its inner extremity into proximity with the surface of the applying roll and serving to limit the thickness of the 20 coating of cement which may be presented to the work by the roll. The upper surface of the scraper also furnishes a table upon which the work may be laid for advance to the applying roll. To vary the effective distance of the end of the scraper from the 25 roll, it carries, rotatably mounted in a depending portion 46, a screw 48, which is threaded into the rear wall of the tank. Since it may be desired to coat portions 30 only of the work passing over the applying roll, the main scraper 44 has mounted at its under side an auxiliary scraper 50, the length of which is sufficient to remove cement from the roll over a portion equal to 35 the width of the area of the work which is to be left uncoated. To alter its relation to the work, the auxiliary scraper is preferably held for adjustment longitudinally of the axis of the roll by screws 52 passing through 40 a slot 54 lying transversely of the main scraper, these screws being threaded into the auxiliary scraper. The position of the auxiliary scraper beneath the main scraper is particularly advantageous, in that the collected cement cleaned from the applying roll falls therefrom into the body of cement contained in the tank. If, instead, the auxiliary scraper were mounted upon the top of 45 the main scraper, there would be a tendency 50 for the portion gathered by the former to accumulate in the space between the two scrapers, thus being returned to the surface just cleaned and also piling up at each side of the cleaned area upon the cement-carrying 55 surface of the roll, causing at these points the application of an excessively thick coating. At the opposite side of the tank from the scraper 44 there is mounted across the top a grating 56 to receive and 60 support the work and permit any excess of cement to be returned therefrom directly to the tank.

Pivoted upon the spindle 34 at the inner side of the inner arm extension 36 is a support 58 for a bearing frame 60. The frame

60 is also pivoted upon its support at 62, the axis of this last-mentioned pivot extending at right angles to the spindle 34, so that movement of the bearing frame is permitted in intersecting planes. Journalized in the 70 frame 60 is a shaft 64, having fast upon it a pressure and feed roll 66 co-operating with the applying roll to hold the work in contact with it and to aid in the advance of such work. Secured to the shaft 64 is a 75 gear 68 meshing with the pinion 30 at one side of the pinion 26, this rotating the pressure roll in the opposite direction to that in which the applying roll is turned. The frame 60 is fixed in position upon the support by a screw 70 passing through an opening in the bearing frame somewhat larger than the diameter of the screw and having its threaded portion engaging the support 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 sisting of an outer or bottom layer A, an inner shank piece B having a front edge *b* beveled upwardly and rearwardly, and an inner forepart piece C provided with an edge for contact with the edge *b* and inclined equally and oppositely thereto. The edges *b* and *c* and opposed surfaces *e* and *f* upon the layer A and the piece C, respectively, are to be secured in contact. This is as illustrated in Fig. 5 of the drawings. The bottom layer A is first passed through the apparatus with the heel portion G projecting beyond the left end of the applying roll, as viewed in Fig. 2, the auxiliary scraper 50 being so positioned upon the main scraper 44 that it will remove from the applying roll the cement which would be laid upon the forepart portion, this causing only the shank portion to be coated. To this coated area the shank piece B is caused to adhere, and then, with the auxiliary scraper removed or out of contact with the applying roll, the work is again introduced between the rolls, this time with the inner or normally upper edge of the shank piece bevel *b* substantially opposite the outer edge of the applying roll (Fig. 2) and the junction of this beveled edge with the area *e* of the layer A opposite the adjacent edge of the roll 66. The pressure applied directly to the forepart portion of the layer A and indirectly to the shank portion forces the surface *e* of the forepart portion against the applying roll, and at the same time urges the beveled surface *b* of the shank piece toward the applying roll, which projects beyond the pressure roll for a distance at least as great as the width of said bevel, straightening these two surfaces *e* and *b* into alignment to allow their perfect presentation to the roll and resulting uniform coating. In this operation the shank and heel portions are displaced upwardly, this being permitted by the space at the end of the pressure roll; see Fig. 2. Perfect contact of the aligned surfaces *e* and *b* with the applying roll may be assured by a preliminary adjustment of the pressure roll upon its support about the pivot 62. Variations in the thickness of the work are taken care of by the yield of the pressure roll with its support about the spindle 34, this movement being in planes intersecting the movement of adjustment just mentioned. The forepart piece C is now applied to this closed area, its bevel *c* being joined to the bevel *b* and its surface *f* to the surface *e*.

Having described my invention, what I claim as new and desire to secure by Letters Patent of the United States is:—

1. In an apparatus for coating objects having surfaces normally inclined with respect to each other, a coating-applying roll, and a pressure roll, said rolls having cooperating surfaces extending opposite each

other from points substantially at the extremities of the respective rolls for a distance as great as the width of one of the surfaces to be coated and the applying roll projecting beyond the pressure roll for a distance as great as the width of the other surface to be coated.

2. In an apparatus for coating a surface of a main sole layer and an adjacent beveled edge of an attached layer, a coating-applying roll, and a pressure roll, said rolls having co-operating surfaces extending opposite each other from points substantially at the extremities of the respective rolls for a distance as great as the length of the surface of the main sole layer and the applying roll projecting beyond the pressure roll for a distance as great as the width of the beveled edge of the attached layer.

3. In a coating apparatus, a coating-applying roll, a co-operating roll, a movable mounting for one of the rolls arranged to permit the angular relation between the axes of said rolls to be varied, and means for fixing the mounting against movement in its adjusted position.

4. In a coating apparatus, a coating-applying roll, a co-operating roll, a pivotal mounting for one of said rolls arranged to turn about an axis substantially at right angles to the axis of such pivotal roll, a mounting for the associated roll fixed relatively to the pivotal mounting, and means for fixing the mounting against movement upon its pivot.

5. In a coating apparatus, a coating-applying roll, a co-operating roll, a movable mounting for one of the rolls arranged to permit the angular relation between the axes of said rolls to be varied, means for fixing the mounting against movement in its adjusted position, and means arranged to permit the yield of one of the rolls.

6. In a coating apparatus, a coating-applying roll, a co-operating roll, a pivotal mounting for one of said rolls, means arranged to normally prevent the mounting from turning in either direction about its pivot, and to release such mounting for angular adjustment, and means arranged to permit the yield of the roll and its mounting.

7. In a coating apparatus, a main frame, a roll journaled therein, a bearing frame mounted to move in intersecting planes upon the main frame, and a roll journaled in the bearing frame, one of the rolls being a coating-applying roll.

8. In a coating apparatus, a coating-applying roll, a co-operating roll, a plurality of movable mountings for one of the rolls, one of said mountings being supported for movement upon another, and means arranged to secure the mounting against movement upon the associated mounting.

9. In a coating apparatus, a coating-applying roll, a co-operating roll, a plurality of pivoted mountings for one of the rolls, and means arranged to secure one of the 5 mountings against movement upon another.
10. In a coating apparatus, a coating-applying roll, a co-operating roll, a yieldable pivoted mounting for one of the rolls, a mounting pivoted upon the yieldable mounting, and means arranged to adjustably fix the position of the mounting carried by the yieldable mounting.
11. In a coating apparatus, a coating-applying roll, a co-operating roll, a movable 15 mounting for one of the rolls, and means arranged to permit the establishment and maintenance of parallelism between the axis of the movable roll and that of the associated roll.
12. In a coating apparatus, a main frame, a coating-applying roll journaled therein, a support pivoted upon the main frame, means arranged to vary the normal position of the support, a bearing frame pivoted upon the support, means arranged to fix the bearing frame in position, and a pressure roll journaled in the bearing frame.
13. In a coating apparatus, a main frame, a coating-applying roll journaled therein, 20 a spindle mounted in said frame, a support turning upon the spindle, a bearing frame pivoted upon the support, a pressure roll journaled in the bearing frame, and means for fixing the bearing frame to the support.
14. In a coating apparatus, a main frame, a coating-applying roll journaled therein, a spindle mounted in said frame, a support turning upon the spindle, a bearing frame pivoted upon the support, a pressure roll 25 journaled in the bearing frame, means for fixing the bearing frame to the support, and an adjusting member for the support contacting with the main frame.
15. In a coating apparatus, a main frame, 30 a coating-applying roll journaled therein, a spindle mounted in said frame, a support turning upon the spindle, a bearing frame pivoted upon the support, a pressure roll journaled in the bearing frame, means for fixing the bearing frame to the support, and an adjusting member for the support contacting with the main frame.
16. In a coating apparatus, a main frame, a coating-applying roll journaled therein, 35 a spindle mounted in said frame, a support turning upon the spindle, a bearing frame pivoted upon the support, a pressure roll journaled in the bearing frame, means for fixing the bearing frame to the support, an adjusting member for the support contacting with the main frame, and a spring co-operating with the main and bearing frames.
17. In a coating apparatus, a main frame, a coating-applying roll journaled therein, 40 a spindle mounted in said frame, a support turning upon the spindle, a bearing frame pivoted upon the support, a pressure roll journaled in the bearing frame, means for fixing the bearing frame to the support, a guide for the bearing frame rotatable about the spindle, and a variable connection between the guide and bearing frame.
18. In a coating apparatus, a receptacle, an applying roll rotatable therein, a main 45 scraper extending over the top of the receptacle into co-operation with the roll, and an auxiliary scraper secured to the under side of the main scraper.
19. In a coating apparatus, a receptacle having ways at its upper portion, an applying roll rotatable in the receptacle, a main scraper mounted in the ways and co-operating with the roll, and an auxiliary scraper variable in position upon the under side of the main scraper.
- In testimony whereof I have signed my name to this specification.

JOHN W. COSGROVE.
